(57) **ABSTRACT**

A rhamnolipid ester is useful as a cosmetic additive. A method of its production involves providing at least one rhamnolipid, reacting the at least one rhamnolipid with at least one coupling reagent, reacting the at least one rhamnolipid with a polyhydric alcohol having 1 to 32 carbon atoms, and optionally purifying the at least one rhamnolipid ester.

RHAMNOLIPID OLIGO-ESTERS

CROSS-REFERENCE TO RELATED APPLICATIONS

This application is the National Stage entry under § 371 of International Application No. PCT/EP2021/069280, filed on Jul. 12, 2021, and which claims the benefit of priority to European Application No. 20187101.9, filed on Jul. 22, 2020. The content of each of these applications is hereby incorporated by reference in its entirety.

BACKGROUND OF THE INVENTION

Field of the Invention

The invention relates to new rhamnolipid esters, to a method of their production and also to the use of the rhamnolipid ester as cosmetic additives.

Description of Related Art

EP3419985 discloses rhamnolipid esters of rhamnolipids with aliphatic alcohols having 7 to 32 carbon atoms

WO2019038125 discloses a dispersion, in particular an emulsion, containing at least one rhamnolipid derivative and also to the use of the rhamnolipid derivatives as emulsifier or dispersing aid, wherein the rhamnolipid derivatives are certain rhamnolipid esters or rhamnolipid amides. Miao et al., *Journal of Surfactants and Detergents*, 17 (6), 2014; 1069-1080, describes the synthesis of di-rhamnolipid ethyl esters by esterification with ethanol and also the suitability of the esters as nonionic surfactant.

WO2001010447 and EP1889623 disclose the pharmaceutical and cosmetic applications of rhamnolipids and short-chain rhamnolipid esters (C1-C6; methyl to hexyl esters, linear or branched), in particular in wound healing.

WO2018195613 discloses a deodorant composition for controlling body odor of localized areas of the body, such as the underarm, or textiles, wherein the composition comprises specific components in particular amounts combined with rhamnolipids for acting specifically on *Corynebacterium xerosis*.

WO2008013899 discloses an application for a cleaning formulation comprising 0.01% to 99.9% of rhamnolipid; and the balance being a carrier.

SUMMARY OF THE INVENTION

It is an object of the invention to provide new anti-perspirant substances, which are also suited to suppress body odor.

Surprisingly, it has been found that the rhamnolipid esters described below are able to achieve the set object of the invention.

The present invention therefore provides rhamnolipid esters as described below.

The invention further provides a process for the preparation of the rhamnolipid esters according to the invention, and the use thereof.

One advantage of the present invention is that the rhamnolipid esters of the instant invention have excellent properties in the reduction of malodors and control sweating.

Another advantage of the present invention is that the rhamnolipid esters of the instant invention can be added to numerous formulation without giving instabilities.

2

A further advantage of the present invention is that the rhamnolipid esters according to the invention increase the mildness of formulations.

A yet further advantage of the present invention is that a process for the preparation of the rhamnolipid esters according to the invention can be performed at industrial scale on standard assets.

A further advantage of the present invention is that the compositions according to the invention potentially decrease the release of zinc and aluminium into the environment, as the rhamnolipid esters of the instant invention are an excellent alternative.

A yet further advantage is that the preparation process is after application of the rhamnolipid esters of the instant invention, the skin becomes less defatted and skin hydration is improved.

A further advantage is that the product can be isolated and worked up in an excellent manner.

A yet further advantage is that the rhamnolipid esters according to the invention do not cause unwanted skin irritation, while leaving a good smooth, silky-soft skin feel.

The terms "rhamnolipid" and "rhamnolipid ester" in connection with the present invention also always include their corresponding salts.

The terms "rhamnolipid radical" in connection with the present invention is understood as that part of the general formula (I) shown below, that is within the z-indexed bracket.

The term "di-rhamnolipid" in connection with the present invention is understood as meaning compounds of the general formula (I) shown below, where A=H and z=1 or salts thereof, in which n=1.

The term "mono-rhamnolipid" in connection with the present invention is understood as meaning compounds of the general formula (I) shown below, where A=H and z=1 or salts thereof, in which n=0.

Distinct rhamnolipids are abbreviated according to the following nomenclature:

"diRL-CXY" is understood as meaning di-rhamnolipids of the general formula (I), where A=H and z=1 or salts thereof, in which one of the radicals R¹ and R²=(CH₂)_o—CH₃ where o=X-4 and the remaining radical R¹ or R²=(CH₂)_o—CH₃ where o=Y-4.

"monoRL-CXY" is understood as meaning mono-rhamnolipids of the general formula (I), where A=H and z=1 or salts thereof, in which one of the radicals R¹ and R²=(CH₂)_o—CH₃ where o=X-4 and the remaining radical R¹ or R²=(CH₂)_o—CH₃ where o=Y-4.

The nomenclature used therefore does not distinguish between "CXY" and "CYCX".

For rhamnolipids where m=0, monoRL-CX or diRL-CX is used accordingly.

If one of the abovementioned indices X and/or Y is provided with "N", this signifies that the respective radical R¹ and/or R²=an unbranched, unsubstituted hydrocarbon radical having X-3 or Y-3 carbon atoms having N double bonds.

Analogous nomenclature is used for rhamnolipid esters in the form di/monoRL-CXY:N esters.

The "pH" in connection with the present invention is defined as the value which is measured for the corresponding substance at 25° C. after stirring for 5 minutes using a pH electrode calibrated in accordance with ISO 4319 (1977).

Unless stated otherwise, all percentages (%) given are percentages by mass.

The present invention provides rhamnolipid ester of the general formula (I)

general formula (I),

where

m =independently of one another, identical or different, 2, 1 or 0, in particular 1 or 0,

n =independently of one another, identical or different, 1 or 0, in particular 1,

z =2 to 10, in particular 2 to 4, most preferably 2,

R^1 =independently of one another, identical or different, organic radical having 2 to 24, preferably 5 to 13, carbon atoms, in particular optionally branched, optionally substituted, in particular hydroxy-substituted, optionally unsaturated, in particular optionally mono-, bi- or tri-unsaturated, alkyl radical, preferably one selected from the group consisting of pentenyl, heptenyl, nonenyl, undecenyl and tridecenyl and $(CH_2)_o-CH_3$ where o =1 to 23, preferably 4 to 12,

R^2 =independently of one another, identical or different, organic radical having 2 to 24, preferably 5 to 13, carbon atoms, in particular optionally branched, optionally substituted, in particular hydroxy-substituted, optionally unsaturated, in particular optionally mono-, bi- or tri-unsaturated, alkyl radical, preferably one selected from the group consisting of pentenyl, heptenyl, nonenyl, undecenyl and tridecenyl and $(CH_2)_o-CH_3$ where o =1 to 23, preferably 4 to 12, and A is a z -valent organic radical.

DETAILED DESCRIPTION OF THE INVENTION

Preferred rhamnolipid esters according to the instant invention are those, where the rhamnolipid radical is selected from the radicals of diRL-C10C10, diRL-C8C10, diRL-C10C12, diRL-C10C12:1 and monoRL-C10C10.

Particularly preferred rhamnolipid esters according to the instant invention are characterized in that $z=2$ and A is selected from the group of two valent hydrocarbyl radicals, which can be substituted by one or more hydroxyl group, preferably selected from the group consisting of

where

R^3 and R^4 are selected from CH_3 and H, $r=0$ to 3,

$s=0$ to 24, and

$t=0$ to 24,

wherein the structures with

$R^3=R^4=H$, $r=t=0$, $s=0$ to 24, preferably 1 to 14,

$R^3=H$, $R^4=CH_3$, $r=0$, $s=0$ to 2, $t=0$ to 23, preferably 1 to 15,

$R^3=CH_3$, $R^4=CH_3$, $r=0$ to 3, $s=0$ to 2, $t=0$ to 23, preferably 1 to 15,

are more preferred,

with the structures with

$R^3=R^4=H$, $r=t=0$, $s=0$ to 8, 10, 12 or 14,

$R^3=H$, $R^4=CH_3$, $r=0$, $s=0$ or 1, $t=0$,

$R^3=H$, $R^4=CH_3$, $r=0$, $s=0$, $t=3, 7, 9, 11$ or 13,

$R^3=CH_3$, $R^4=CH_3$, $r=s=2$, $t=0$,

are most preferred.

Other particularly preferred rhamnolipid esters according to the instant invention with $z=2$ and A is selected from the group of two valent hydrocarbyl radicals, which can be substituted by one or more hydroxyl group, have A selected from

Alternatively particularly preferred rhamnolipid esters according to the instant invention are characterized in that $z=2$ and A is selected from the group of

5

6

Further alternatively particularly preferred rhamnolipid esters according to the instant invention are characterized in that $z=2$ and A is selected from the group of

Particularly preferred rhamnolipid esters according to the instant invention are characterized in that $z=2$, the rhamnolipid radical is selected from the radicals of diRL-C10C10, diRL-C8C10, diRL-C10C12, diRL-C10C12:1 and monoRL-C10C10, and A is selected from the group of

where

$R^3=R^4=H$, $r=t=0$, $s=0$ to 8 , 10 , 12 or 14 ,

Particularly preferred according to the instant invention the rhamnolipid esters constitute a mixture composition of different rhamnolipid ester of the general formula (I).

The rhamnolipid esters according to the invention are preferably mixture compositions of rhamnolipid esters which are characterized in particular in that they contain mono- and di-rhamnolipid esters and/or mixed mono-/di-rhamnolipid esters, the latter being characterized by at least one mono-rhamnolipid-radical and at least one di-rhamnolipid-radical in one molecule.

Depending on the application, it may be preferred that in the mixture compositions according to the invention there are more percent by weight of mono-rhamnolipid-radicals than di-rhamnolipid radicals or more percent by weight of di-rhamnolipid-radicals than mono-rhamnolipid-radicals, where the percentages by weight refer to all of the mono- and di-rhamnolipid-radicals present in the rhamnolipid-ester.

Thus, for example, the rhamnolipid-ester as mixture composition according to the invention can comprise, for example, more than 60% by weight, in particular more than 80% by weight, or even more than 95% by weight, of di-rhamnolipid radicals, or else also for example more than 60% by weight, in particular more than 80% by weight, or even more than 95% by weight, of mono-rhamnolipid radicals, where the percentages by weight refer to all of the mono- and di-rhamnolipid radicals present in the rhamnolipid-ester.

The present invention further provides a process for the preparation of rhamnolipid esters comprising the process steps

- 45 A) provision of at least one rhamnolipid,
- B) reaction of the rhamnolipid with at least one coupling reagent,
- C) reaction of the rhamnolipid activated by process step B) with a polyhydric alcohol having 1 to 32 carbon atoms, and optionally
- D) purification of the rhamnolipid ester.

Process step A) is carried out according to the generally known processes of the prior art, in particular using genetically modified microorganisms which preferably overexpress rhamnolipid synthesis genes, these genes preferably being selected from rhlA, rhlB and rhlC. Corresponding instructions can be found by the person skilled in the art in e.g. US2014296168 and WO2012013554.

It is preferred according to the invention that in process step B) the coupling reagent used is at least one selected from the group comprising, preferably consisting of, dicyclohexylcarbodiimide, diisopropylcarbodiimide, 1-(3-dimethylaminopropyl)-3-ethylcarbodiimide hydrochloride, N-cyclohexyl-N'-(2'-morpholinoethyl)carbodiimide metho-p-toluenesulphonate, N-benzyl-N'-3' dimethylaminopropylcarbodiimide hydrochloride, 1-ethyl-3-(3-dimethylaminopropyl)carbodiimide, N-ethylcarbodiimide hydrochloride

and carbonyldiimidazole, particularly preferably dicyclohexylcarbodiimide and diisopropylcarbodiimide.

Likewise, it is preferred according to the invention that in process step C) at least one catalyst selected from the group comprising, preferably consisting of, N-ethylidisisopropylamine, trialkylamines, pyridine, 4-dimethylaminopyridine and hydroxybenzotriazole, in particular hydroxybenzotriazole, is used.

Processes preferred according to the invention preferably lead to the rhamnolipid esters which are described as preferred rhamnolipid esters according to the invention above.

Thus, for example, preferably in process step A) preferably rhamnolipids selected from diRLC10C10, diC8C10, diRLC10C12, diRLC10C12:1 and monoRLC10C10 or mixtures thereof are used.

Accordingly the use of alcohols in process step C) is preferred selected from the group of 1,2-ethanediol, 1,2-propanediol, 1,3-propanediol, 1,4-butanediol, 1,3-butane-
diol, 1,5-pentanediol, 1,2-hexanediol, 2,5-hexanediol, 1,6-
hexanediol, 1,7-heptanediol, 1,8-octanediol, 2,6-
dimethyloctane-1,8-diol, 1,9-nanediol, 1,10-decanediol,
1,2-decanediol, 2,2,9,9-tetramethyl-1,10-decanediol, 1,12-
dodecanediol, 1,2-dodecanediol, 1,2-tetradecanediol, 1,14-
tetradecanediol, 1,16-hexadecanediol and 1,2-hexadecane-
diol.

The use of alcohols in process step C) selected from the group 1,4-cyclohexanediol, 1,2-cyclohexanediol, 1,3-cyclohexanediol, 1,2-cyclopentanediol, 1,3-cyclopentanediol, 4,4-dimethyl-1,2-cyclopentanediol, 4-cyclopentene-1,3-diol, 3-cyclopentene-1,2-diol, 2-tea-butyl-1,4-cyclohexanediol, 2-methyl-1,4-cyclohexanediol, 1,3-cyclohexanediethanol, 1,4-cyclohexanediethanol, 4,4'-isopropylidenedicyclohexanol and 4,4'-bicyclohexanol, is alternatively preferred.

The use of alcohols in process step C) selected from the group 1,4-benzenediol, methylhydroquinone, 1,2-benzenediol, 1,3-benzenediol, 1,3-dihydroxy-4-methylbenzene, 4-methyl-1,2-benzenediol, 3,5-dihydroxytoluene, 2,6-dihydroxytoluene, 4-butyl-1,3-benzenediol, 4-hexylresorcinol, 1,4-benzenedimethanol and 1,4-bis(2-hydroxyethyl)benzene is alternatively preferred.

The use of alcohols in process step C) selected from the group 1,2-ethanediol, 1,3-propanediol, 1,4-butanediol, 1,5-pentanediol and 1,6-hexanediol, 1,8-octanediol, 1,10-decanediol, 1,12-dodecanediol, 1,4-cyclohexanediethanol, 1,4-Cyclohexanediol, 1,4-benzenedimethanol and 1,4-bis(2-hydroxyethyl)benzene is very much preferred.

The invention further provides the rhamnolipid esters obtainable by the process according to the invention,

The rhamnolipid esters according to the invention can advantageously be incorporated into in particular cosmetic formulations, preferably for anti-perspirant applications.

Consequently, the present invention further provides the use of the rhamnolipid esters according to the invention

for producing formulations, in particular cosmetic formulations,

and the formulations themselves, in particular cosmetic formulations, preferably for anti-perspirant applications, which comprise the rhamnolipid esters according to the invention.

The formulations according to the invention are preferably aqueous formulations.

The term "aqueous formulation" in connection with the present invention is to be understood as meaning a formulation which comprises at least 5% by weight of water, based on the overall composition under consideration.

According to the invention, it is preferred if the formulations according to the invention comprise the rhamnolipid esters according to the invention in an amount of from 0.05% by weight to 40% by weight, preferably from 0.1% by weight to 20% by weight, particularly preferably from 0.2% by weight to 5% by weight, where the percentages by weight refer to the total formulation.

Preferred formulations according to the invention comprise, in addition to the rhamnolipid esters according to the invention, at least one further additional component.

The formulations according to the invention can further comprise at least one additional component selected from the group of

emollients,
emulsifiers,
thickeners/viscosity regulators/stabilizers,
UV light protection filters,
antioxidants,
hydrotropes (or polyols),
solids and fillers,
film formers,
pearliscence additives,
deodorant and antiperspirant active ingredients,
insect repellents,
self-tanning agents,
surfactants,
perfumes,
preservatives,
propellants,
conditioners,
dyes,
cosmetic active ingredients,
care additives,
superfatting agents,
solvents,
wherein perfumes, antiperspirant active ingredients and propellants are preferably comprised.

Substances which can be used as exemplary representatives of the individual groups are known to the person skilled in the art and can be found for example in the German application DE 102008001788.4. This patent application is herewith incorporated as reference and thus forms part of the disclosure.

As regards further optional components and the amounts used of these components, reference is made expressly to the relevant handbooks known to the person skilled in the art, for example K. Schrader, "Grundlagen und Rezepturen der Kosmetika [Fundamentals and principles of cosmetics]", 2nd edition, pages 329 to 341, Hüthig Buch Verlag Heidelberg.

The amounts of the particular additives are governed by the intended use.

Typical guide formulations for the respective applications are known prior art and are contained for example in the brochures of the manufacturers of the particular basic materials and active ingredients. These existing formulations can usually be adopted unchanged. If necessary, the desired modifications can, however, be undertaken without complication by means of simple experiments for the purposes of adaptation and optimization.

The rhamnolipid esters according to the invention and the formulations according to the invention comprising the rhamnolipid esters according to the invention can be used advantageously for inhibiting body odor.

The present invention further provides the cosmetic use of the rhamnolipid esters according to the invention and/or of the formulations according to the invention in anti-perspirant applications.

The present invention further provides the cosmetic use of the rhamnolipid esters according to the invention and/or of the formulations according to the invention for inhibiting sweat.

The examples listed below describe the present invention by way of example, without any intention of restricting the invention, the scope of application of which is apparent from the entirety of the description, to the embodiments specified in the examples.

EXAMPLES

Example 1: Preparation of Di-Rhamnolipids

A fermentation with a recombinant strain *Pseudomonas putida* KT2440S pBBR¹MCS2-Plac-rhIABC-T-Ptac-rhIC-T was carried out. The construction of the strain was described in US2014296168. The preculture in the shake flask was carried out as described in WO2012013554. For the main culture, a mineral medium (M9) was likewise used. The fermentation takes place in a glucose-limited fed-batch process in a 2 litre fermenter. The feeding in of glucose was regulated by reference to the dissolved-oxygen signal. The oxygen partial pressure of the fermentation broth was regulated at 20% saturation via the stirrer speed. The pH was regulated to 7 via a pH electrode and addition of 2M sulphuric acid or of a 20% by weight ammonia solution. In order to prevent excessive foaming of the fermentation broth, the antifoam DOW Corning 1500 was metered in as required. The fermentation was conducted over 4 days to a dry biomass of 15 Wt. The rhamnolipid concentration was determined by HPLC and was 9.8 g/l. After separating off the cells by means of centrifugation at 10 000 g, the fermentation broth was adjusted to a pH of 3.1 by adding concentrated H₂SO₄. Renewed centrifugation gave a pasty solid concentrate with an RL fraction of 45% by weight and with a viscosity of >10 000 mPas. With continuous stirring, a 50% strength by weight aqueous KOH solution was added to the pasty suspension of the concentrated rhamnolipid precipitate and a pH of 6 was established. The pasty mass liquefied at this point with an accompanying sharp drop in viscosity. The suspension gave rise to a clear solution. By adding water, the solution was adjusted to an active content of 35% by weight. The rhamnolipid purity was >90% by weight, based on the dry mass. For the synthesis the rhamnolipid was freeze-dried.

Rhamnolipid species verified by HPLC were:

RL total [%] (HPLC)	91
diRL-C8C10	13.9
monoRL-C8C10	0.51
diRL-C10C10	61.4
monoRL -C10C10	1.4
diRL-C10C12:1	5.9
diRL-C10C12	5.5
other RL	2.2

Example 2: Preparation of Mono-Rhamnolipids

The 35% by weight rhamnolipid solution prepared as described above was diluted to 1% by adding water. Two

litres of this solution were heated to 50° C. With gentle stirring, 200 units of a thermostable rhamnosidase (ThermoActive™ Rhamnosidase A, Prokazyme) were added and the reaction was carried out overnight. After 20 h, a sample of the solution was analysed by means of HPLC. The di-rhamnolipid had been completely converted to mono-rhamnolipid and rhamnose. Then, the enzyme was deactivated for one hour at 80° C. The entire mixture was freeze-dried.

Example 3: Synthesis of Di-Rhamnolipid-Di-Ester

1

25 g of freeze-dried di-rhamnolipid from example 1 with 6.6 ml of diisopropylcarbodiimide were dissolved in THF and stirred under nitrogen at 55° C. for 1 hour. Next 1.6 grams of 1,4-butanediol and 1% (w/w) of 4-dimethylaminoypyridine were added and stirring was continued at 55° C. for 20 h. The reaction was quenched by adding 2 ml of water and the mixture was stirred and slowly cooled to 2° C. and stirring continued for 2 hours. The solids were filtered off over a glass filter. The cake was washed with a mixture of ethanol and water (6:1). Further purification could be achieved by reverse liquid chromatography.

Example 4: Synthesis of Di-Rhamnolipid-Di-Ester

2

A mixture 25 g of freeze-dried di-rhamnolipid from example 1 with 4.4 grams of N-Hydroxy-succinimide (HSU) were dissolved in THF and stirred under nitrogen at RT for 1 hour. 6.6 ml of diisopropylcarbodiimide was added into the mixture over a period of ca 10 minutes, rinsed with 2 ml of THF. The mixture was stirred at 55° C. for 1 hour. Next 2 grams of 1,4-cyclohexanediol were added and stirring was continued at 55° C. for 7 hours and at 50° C. overnight. The next day 2 ml of water were added to quench the reaction. The mixture was distilled half off and additional 50 ml methanol were added and the mixture was stirred at 50° C. The turbid mixture was slowly cooled to 2° C. and stirred for 5 hours. The solids were filtered off over a glass filter. The cake was washed with a mixture of ethanol and water (6:1). Further purification could be achieved by reverse liquid chromatography.

Example 5: Synthesis of Mono-Rhamnolipid-Di-Ester 1

25 g of freeze-dried mono-rhamnolipid from example 2 with 6.9 ml of diisopropylcarbodiimide were dissolved in THF and stirred under nitrogen at 55° C. for 1 hour. Next 2.6 grams of 1,6-hexanediol and 1% (w/w) of 4-dimethylaminoypyridine were added and stirring was continued at 55° C. for 20 h. The reaction was quenched by adding 2 ml of water and the mixture was slowly cooled to 2° C. under stirring and continued for 2 hours. The solids were filtered off over a glass filter. The cake was washed with a mixture of ethanol and water (6:1). Further purification could be achieved by reverse liquid chromatography.

Example 6: Synthesis of Mono-Rhamnolipid-Di-Ester 2

A mixture 25 g of freeze-dried mono-rhamnolipid from example 2 with 5.7 grams of N-Hydroxy-succinimide (HSU) were dissolved in THF and stirred under nitrogen at RT for 1 hour. 8.5 ml of diisopropylcarbodiimide were added

11

to the mixture over a period of ca 10 minutes, rinsed with 2 ml of THF. The mixture was stirred at 55° C. for 1 hour. Next 3.2 grams of 1,4-cyclohexanedimethan were added and stirring was continued at 55° C. for 7 hours and at 50° C. overnight. The next day 2 ml of water were added to quench the reaction. The mixture was distilled half off and additional 50 ml methanol were added and the mixture was stirred at 50° C. The turbid mixture was slowly cooled to 2° C. and stirred for 5 hours. The solids were filtered off over a glass filter. The cake was washed with a mixture of ethanol and water (6:1). Further purification could be achieved by reverse liquid chromatography.

Example 7: Synthesis of Mixed Mono/Di-Rhamnolipid-Di-Ester

A mixture 20 g of freeze-dried di-rhamnolipid from example 1, 15 g of mono-rhamnolipid from example 2 and 11 ml of diisopropylcarbodiimide were dissolved in THF and stirred under nitrogen at 55° C. for 1 hour. Next 2.5 grams of 1,4-Butanediol and 1% (w/w) of 4-dimethylaminopyridine were added and stirring was continued at 55° C. for 20 h. The reaction was quenched by adding 4 ml of water and the mixture was stirred and slowly cooled to 2° C. and stirred for 5 hours. The solids were filtered off over a glass filter. The cake was washed with a mixture of ethanol and water (6:1), dried at 40° C. over night under vacuum.

Example 8: Application Effects

In order to measure the influence of the specified structures on producing underarm sweating and odor. The fol-

12

lowing application tests with the formulations according to the invention were carried out.

The following formulations were prepared 24 hours before use. Typically, 500 g of formulation were prepared in a 800 mL beaker. If ingredients/phases need to be heated, a water bath was used. Mixing was done by a four-blade-stirrer, driven by a Eurostar 20 digital by IKA (IKAWerke, Staufen, Germany) if not otherwise stated.

10

Example 8.1

500 g of the formulation were prepared as follows: Oils (Phase A) and aqueous phase (Phase B, part of the water, butylene glycol and, if indicated the inventive structures) were mixed separately and heated up under stirring to 80° C. The rest of the water and PEG-6000 Distearate were also mixed separately and heated to 80° C.

15 20 Phase B was slowly added to phase A while stirred with a four-blade-stirrer at 250 rpm in a 800 mL beaker within 5 minutes. Then, phase C was added within 1 minute, the mixture is still mixed and kept at 80° C. during the process. After addition of phase C, the mixture was stirred well (1000 25 rpm, 3 minutes), and then allowed to cool down to 40° C. with gentle stirring (100 rpm). Phase D was added at 40° C. under well stirring (1000 rpm, 3 minutes), phase E was then added under stirring (1 minute, 250 rpm). The whole mixture then needs to cool down to room temperature under well stirring (1000 rpm).

Phase	8.1.1	8.1.2	8.1.3	8.1.4	8.1.5	8.1.6	8.1.7

Formulations 8.1.3 to 8.1.7 are formulations according to the instant invention

50

Example 8.2

The following formulations were prepared:

Water (phase A) was heated to 75° C. to dissolve the 55 Xanthan Gum (phase B) while stirring (at least 15 minutes, 1000 rpm). The mixture was then cooled to room temperature (100 rpm) to add the ethanol (Phase C). Then, all other ingredients (Phase D) can be added under slight mixing (100 rpm-250 rpm).

Formulations 8.2.2 to 8.2.7 are formulations according to the instant invention

Example 8.3

This deo-stick formulation was prepared 48 hours before application to allow the formulation to solidify completely.

Glycol, glycerine and water (Phase A) were heated to 60° C. and the sodium hydroxide was added (phase B). This mixture was then heated under stirring (100 rpm) to 90° C. and the fatty acids are added (phase C). The mixture was

15 mixed at 90° C. until it appears homogeneously (typically 60 minutes, 100 rpm). The pH of the formulation was checked (dilution of a small part of the formulation with water), pH-value should be between pH 8 and pH 9. The hot mixture was then filled into deo stick tubes and allowed to solidify at room temperature within 24 hours to give light yellowish 20 pasty sticks.

Phase	8.3.1	8.3.2	8.3.3	8.3.4	8.3.5	8.3.6	8.3.7

di-Rhamnolipid hexylester was prepared as described in example 3 of WO2017144317; instead of lauryl-alcohol, n-hexyl alcohol was used at equal molar amount.

Example 8.4

45 After phases A and B were prepared separately at room temperature, phase A was added to phase B under stirring (300 rpm, 1 minute). The mixture was then homogenized (5 minutes, 1800 rpm) to obtain a lotion. Then the polymers were added (Phase C) under stirring, followed by a short 50 homogenization step (0.5 minutes, 300 rpm, 1 minute 1800 rpm). Finally, the sodium hydroxide was added (phase D) under stirring (10 minutes, 500 rpm) to obtain a lotion.

di-hamnolipid ethylester was prepared as described in example 4 of WO2017144317.
di-hamnolipid octylester was prepared as described in example 3 of WO2017144317; instead of lauryl-alcohol, n-octyl alcohol was used at equal molar amount.

Example 8.6

Formulating this water-in-oil emulsion requires the help of a ultra-turrax® (T 18 digital ultra-turrax, Ika, Ika Werke, Staufen, Germany).

The liquid components of phase A were mixed with a spatula. Then first the zinc stearate was incorporated into the oil phase by the ultra turrax (3 minutes, 10.000 rpm) before the Aerosil was added in similar way (3 minutes, 10.000 rpm). The aqueous phase (phase B) was also mixed with a spatula at room temperature and then slowly added in phase A with minimum input of mixing (2 minutes, 3000 rpm). After complete addition of phase B, the white emulsion was homogenized for short time (1 minute, 10.000 rpm) and filled into applicators.

di-Rhamnolipid ethylester was prepared as described in example 4 of WO2017144317.

di-Rhamnolipid octadecyllester was prepared as described in example 3 of WO2017144317; instead of lauryl-alcohol, n-octadecyl alcohol was used at equal molar amount.

Example 9: Panel Testing

Eight panelists were selected for odor tests (panelists are coded with letters A-H). Every panelist was equipped with a wash lotion as described in table 1.

by the examiner. After all six examiners gave their evaluation on one panelists, the difference of the pairwise evaluation is averaged. A difference of the average of 1 is likely to be experienced by an untrained person, whereas a difference of 2 or more is clearly recognized.

TABLE 1

perfume free wash lotion for cleaning of underarms of panelists			
INCI	Tradename/Supplier	Active matter/ %	Concentration/ %
water			13.7
PEG-7 Glyceryl Cocoate	TEGOSOFT ® GC/Evonik	100	5.4
Sodium Laureth Sulfate	Texapon NSO/BASF	28	65.80
Cocamidopropyl Betaine; Glyceryl Laurate	TEGO ® Betain HS/Evonik		10.00
PEG-18 Glyceryl Oleate/Cocoate	ANTIL ® 171/Evonik	100	4.10
Verstatil PC	Phenoxyethanol, Caprylyl Glycol/Evonik	100	1

This wash lotion was free of perfumes to avoid an influence of artificial odors on the panel results.

The panelists were asked to clean their armpits as usual in their daily routine, however, the panelists used the perfume free wash lotion provided. After cleaning, the formulations described in the section above were applied. The formulations were packed in neutral containers which were randomly labeled. Thus, the inventive formulations were applied also randomly under the left or the right arm. The panelists were also advised to use no additional perfume. The panelists applied the formulations in the morning and the degree of malodor was accessed after 8-10 hours after application. The panelists followed the normal working routine, the artificial sweat generation in hot rooms was not used since the formulations were evaluated in pairwise discrimination.

Six trained examiners evaluated the malodor intensity scale of the panelists after 8-10 hours. The ratings were given according to the malodor intensity scale ranging from 0 to 10. (see IFSCC Monograph, Number 6, "Antiperspirants and Deodorants: Principles of Underarm Technology" Copyright © International Federation of the Societies of Cosmetic Chemists 1998; ISBN 1-870228-19-7 and Table 2).

The examiners scored the odor of the armpits of the panelists, the difference of the evaluation were calculated per examiner to visualize the pairwise difference perceived

TABLE 2

malodor intensity scale used for description of odor by the examiners		
	Score	malodor intensity scale
	0	None, no odor
	1	Threshold odor
	2	Very slight odor
	3	Slight odor
	4	Slight to moderate odor
	5	Moderate odor
	6	Slightly strong odor
	7	Moderately strong odor
	8	Strong odor
	9	Very strong odor
	10	Extremely strong odor

Example 9.1

In a first experiment, formulations 8.1.1 and 8.1.2 were tested. Both formulations contain no molecules according to the instant invention. The difference in loading of aluminium salts should be investigated in that set.

	Examiner	1	2	3	4	5	6	difference 8.1.2 to 8.1.1

		-3	-4	-4	-2	-3	-4	-3.33 3.33
Average of differences over all panellists								3.79

Results: It is obvious that the formulation with 20% aluminium salt (8.1.1) outperformed the formulation with 10% salt (8.1.2).

Example 9.2

The next set of experiments was made in order to see if the inventive structures can compensate the lower level of aluminium salt. Thus formulation 8.1.1 (20% aluminium salt) was tested against formulation 8.1.4 (10% aluminium salt+inventive structure 4)

	Examiner	1	2	3	4	5	6	difference 8.1.1 to 8.1.4
Panelist A	left 8.1.1	2	3	1	2	3	2	
	right 8.1.4	2	1	2	1	2	3

Panelist L	right 8.5.6	3	4	5	5	5	4	
		-5	-3	-1	-3	-2	-4	-3.00
Average of differences over all panellists								3.21

Results: The set of data clearly shows that the inventive oligo ester of mono-rhamnolipid is better suited in reduction of malodor as compared to the mono-ester.

List of Ingredients Used

INCI	Tradename	Supplier
Isoceteth-20	Tego Alkaonol IC 20	Evonik
Diethylhexyl Carbonate	Tegosoft DEC	Evonik
Triisostearin	Tegosoft TIS	Evonik
Glyceryl Isostearate	Sympatens-GMIS	KLK Oleo Europe
Butylene Glycol	Butylene Glycol	Dow
PEG-6000 Distearate	Rewopal PEG 6000 DS	Evonik
PEG-18 Glyceryl Oleate/Cocoate	Antil 171	Evonik
Alumminium Cholorhydrate	Chlorohydrol	Elementis
Xanthan Gum	Satiaxane	Cargill
Ethylalcohol	Ethanol	Cremer Oleo
Propylen Glycol	Propylen Glycol	Dow
Ethylhexylglycerin	Ethylhexylglycerin	Hubei Artec Biotechnology Co., Ltd.
Citric acid	Citric acid	Sigma Aldrich
Panthenol	Panthenol	Parchem
Glycerin	Glycerin	Cremer Oleo
Sodium Hydroxide 10%	Sodium Hydroxide	Sigma Aldrich
Stearic Acid	CremerAC SA 18/92	Cremer Oleo
Palmitic Acid	CremerAC C16/98	Cremer Oleo
Bis-PEG/PPG-16/16 PEG/PPG-16/16 Dimethicone (and) Caprylic/Capric Triglyceride	Abil Care 85	Evonik
Tego SMO 80 V	Polysorbate 80	Evonik
Carbomer	Carbomer 940	Ashland
Mineral Oil	Agrol 13	Sonneborn
Polyglyceryl-6 Stearate (and) Polyglyceryl-6 Behenate (and) C18-22 Hydroxyalkyl Hydroxypropyl Guar	Tego Care APD 18	Evonik
Isopropyl Palmitate	Tegosoft P	Evonik
Bis-PEG/PPG-14/14 Dimethicone; Dimethicone	Abil EM 97 S	Evonik
Cetyl PEG/PPG-10/1 Dimethicone	Abil EM 90	Evonik
Dimethicone 5 mPas	Belsil DM 5	Wacker
Silica	Aerosil R 812	Evonik
Zinc stearate	Zinc stearate	Sigma Aldrich
Sodium Chloride	Sodium Chloride	Sigma Aldrich
Phenoxyethanol, Caprylyl Glycol	Verstatil PC	Evonik
Phenoxyethanol, Ethylhexylglycerin	Euxyl PE 9010	Schülke & Mayr

The invention claimed is:

1. A rhamnolipid (RL) ester of the general formula (I)

general formula (I),
wherein

m=independently of one another, identical or different, 2,

1, or 0,

n =independently of one another, identical or different, 1 or 0,

Z=2 to 10,

R¹=independently of one another, identical or different, an organic radical having 2 to 24 carbon atoms,

R^2 =independently of one another, identical or different, an organic radical having 2 to 24 carbon atoms, and A is a z-valent organic radical.

2. The rhamnolipid ester according to claim 1, wherein a rhamnolipid radical of the general formula (I) is selected from the group consisting of diRL-C10C10, diRL-C8C10, diRL-C10C12, diRL-C10C12:1, and monoRL-C10C10.

3. The rhamnolipid ester according to claim 1, wherein $z=2$, and

A is a two valent hydrocarbyl radical, which can be substituted by one or more hydroxyl groups.

4. The rhamnolipid ester according to claim 1, wherein

$z=2$, and

27

-continued

5. The rhamnolipid ester according to claim 1, wherein $z=2$, and

A is selected from the group consisting of

28

-continued

10 6. The rhamnolipid ester according to claim 1, wherein
a rhamnolipid radical of the general formula (1) is
selected from the group consisting of diRL-C10C10,
diRL-C8C10, diRL-C10C12, diRL-C10C12:1, and
monoRL-C10C10,
15 z=2, and
A is selected from the group consisting of

wherein
 $R^3 = R^4 = H$, $r = t = 0$, $s = 0$ to 8, 10, 12, or 14.

45 7. A formulation, comprising at least one rhamnolipid ester according to claim 1.

8. A cosmetic formulation for anti-perspirant applications, comprising:

the rhamnolipid ester according to claim 1.

50 9. The rhamnolipid ester according to claim 1, wherein in general formula (I),

R^1 =independently of one another, an optionally branched, optionally substituted, and optionally unsaturated alkyl radical; and/or

R²=independently of one another, an optionally branched, optionally substituted, and optionally unsaturated alkyl radical.

60. **10.** The rhamnolipid ester according to claim 1, wherein in general formula (1),

60 R—individually or one another, selected from the group consisting of pentenyl, heptenyl, nonenyl, undecenyl, tridecenyl, and $(CH_2)_o-CH_3$ wherein o=1 to 23.

11. The rhamnolipid ester according to claim 1, wherein

II. The rhamnopyrid ester according to claim I, wherein in general formula (I),

65 R—individually or one another, selected from the group consisting of pentenyl, heptenyl, nonenyl, undecenyl, tridecenyl, and $(CH_2)_o-CH_3$ wherein o=1 to 23.

29

12. The rhamnolipid ester according to claim 3, wherein A is

wherein
 R³ and R⁴ are CH₃ or H,
 r=0 to 3,
 s=0 to 24, and
 t=0 to 24.

13. The rhamnolipid ester according to claim 3, wherein A is

14. A process for the preparation of at least one rhamnolipid ester according to claim 1, comprising:
 A) providing at least one rhamnolipid,
 B) reacting the at least one rhamnolipid with at least one coupling reagent,
 C) reacting the at least one rhamnolipid activated by B with a polyhydric alcohol having 1 to 32 carbon atoms, to obtain the at least one rhamnolipid ester, and

30

optionally,
 D) purifying the at least one rhamnolipid ester.
 15. The process according to claim 14, wherein in B), the at least one coupling reagent is at least one selected from the group consisting of dicyclohexylcarbodiimide, diisopropylcarbodiimide, 1-(3-dimethylaminopropyl)-3-ethylcarbodiimide hydrochloride, N-cyclohexyl-N'-(2'-morpholinoethyl) carbodiimide metho-p-toluenesulphonate, N-benzyl-N'-3' dimethylaminopropylcarbodiimide hydrochloride, 1-ethyl-3-(3-dimethylaminopropyl) carbodiimide, N-ethylcarbodiimide hydrochloride, and carbonyldiimidazole.

16. The process according to claim 14, wherein the reacting in C) is with at least one catalyst selected from the group consisting of N-ethyldiisopropylamine, trialkylamine, pyridine, 4-dimethylaminopyridine, and hydroxybenzotriazole.

17. The process according to claim 14, wherein in A), the at least one rhamnolipid is selected from the group consisting of diRLC10C10, diC8C10, diRLC10C12, diRLC10C12:1, monoRLC10C10, and a mixture thereof.

18. The process according to claim 14, wherein in C), the polyhydric alcohol is at least one selected from the group of 1,2-ethanediol, 1,2-propanediol, 1,3-propanediol, 1,4-butanediol, 1,5-pentanediol, 1,2-hexanediol, 2,5-hexanediol, 1,6-hexanediol, 1,7-heptanediol, 1,8-octanediol, 1,9-nanediol, 1,10-decanediol, 1,12-dodecanediol, 1,2-dodecanediol, 1,2-tetradecanediol, 1,14-tetradecanediol, and 1,16-hexadecanediol.

19. A method, comprising:
 adding the rhamnolipid ester according to claim 1 to a formulation for inhibiting body odor and/or sweat.
